UNITED STATES PATENT OFFICE

CHARLES VERCH, OF ALBANY, NEW YORK

DOORSTOP

Application filed January 25, 1930. Serial No. 423,453.

My invention relates to door stops or devices which are placed at the bottom of a door on the inside to prevent entrance from the outside. In addition to preventing entrance from the outside, my door stop, in its preferred form, includes an audible alarm or, perhaps, more broadly, an alarm or signal actuating means whereby any attempt to force an entrance by moving the door inwardly will effect an actuation of the alarm or place the alarm actuating mechanism in operation.

The objects of my invention are to provide a simple device of this character which may be cheaply manufactured, which may be easily placed in operative position, which will be positive in its operation and which will not only prevent the door from being opened but will also sound an alarm when any attempt is made to force an entrance by moving the door inwardly.

With these objects in view, my invention includes the novel elements and the combinations and arrangements thereof described below and illustrated in the accompanying drawings, in which—

Fig. 1 is a side elevation showing my device in position under the door;

Fig. 2 is a plan view of my device;

Fig. 3 is a section of the base plate on the line 3—3 of Fig. 2; and

Fig. 4 is a fragmentary side elevation showing the relative position of the parts when an attempt is made to open the door by forcing it inwardly.

Referring to the drawings, my device comprises a base plate, 1, which is preferably rectangular when viewed in plan and the upper surface of which is formed of two planes, 2 and 3, intersecting in line, 4, at about the center of the plate. The sides of portion, 3, are provided with depending flanges, 5 and 6, the lower edges of which may be about parallel to the surface, 2. That is, the bottom of the flanges, 5 and 6, are intended to rest upon

the floor so that the portion of the plate, 3, with the flanges will form a wedge adapted to be inserted beneath the door. At about the middle of the plate there is a transverse web, 7, which preferably extends between the flanges, 5 and 6, and forms with the flanges, 5 and 6, and the portion, 3, a recess in the bottom of the plate in which a wedge shape rubber block, 8, may be inserted. This rubber block rests upon the floor or sill, 9, and is intended not only to prevent the device from marring a hard wood sill or floor but also to frictionally engage the floor rather firmly and hold the plate immovable in respect to the floor when the door is forced upwardly along the surface, 3. Inasmuch as the function of the transverse web, 7, is merely to hold the rubber block, 8, in place, it obviously need not extend entirely between the flanges, 5 and 6, but may, if desired, be merely a small lug or projection on the bottom side of the plate. The flanges, 5 and 6, are extended beneath the portion, 2, for a short distance as perhaps is best shown in Fig. 3 at 10. The plate may be of any kind of material and may be cast or stamped. When cast, the portions, 10, are provided with lugs or trunnions, 11, and when stamped, the portions, 10, may be provided with openings in place of the trunnions or lugs through which a long bolt or pin may be inserted in place in the lugs. The purpose of the trunnions, 11, is to form a supporting means for the resilient element, 12, which secures the device to the door. This element comprises a U-shaped, fairly stiff, but resilient wire which is provided at its extremities with upturned points, 13, adapted to be forced into the bottom of the door, 14, as shown in Figs. 1 and 4. The sides of the U-shaped element, 12, are provided, at about the middle, with loops or link-like openings, 17, which fit over the trunnions, 11, and permit the U-shaped element not only to turn freely upon the trunnions but also to have some longitudinal movement.

in respect thereto. The U-shaped element is secured to the plate by slipping the loops or links, 17, over the trunnions, 11, and the ends of the trunnions may be then riveted over to positively secure the U-shaped element in place.

The extreme rear end of the portion, 2, of the plate is provided with a rotatable button-like device, 15, which is pivotally secured to the plate at 16, and which may be turned from the position, 15, to the position, 15', or vice versa.

Mounted on the base plate, 1, by any appropriate means and approximately centrally located on said plate over portion, 2, is an alarm, 18, here shown as a bicycle bell of the well known type which is wound up by turning the gong and which is actuated by pressing the button or alarm actuating means, 19. The particular kind of alarm is not important but the position of the actuating means must be such that when the door is pushed inwardly over the portion, 3, it will come into contact with the alarm actuating means and produce a movement thereof whereby the alarm is actuated. While the alarm which I have shown is an ordinary bicycle bell, it is to be understood that any kind of an alarm may be used.

In operation, my device is applied to the door and is operated as follows: Depending upon the distance between the bottom of the door and the floor or the bottom of the door and the sill, a rubber block, 8, of appropriate thickness is selected and placed in position under the plate, 1, so that the plate, 1, together with the block, 8, forms a wedge-like unit adapted to be forced under the door into the position shown at Figs. 1 and 4. After the base plate is pushed under the door, as shown in Fig. 1, the U-shaped element is pushed towards the door as far as the movement of the links, 17, on the trunnions will permit. In this position the U-shaped element is in the position shown at 12', in Fig. 1, and the button, 15, is in the position shown at 15'. By then depressing the portion, 20, of the U-shaped element, 12, (see Fig. 1) it acts as a lever about the trunnion as a fulcrum and the points, 13, are forced into the bottom of the door. The portions, 20, of the U-shaped element is thus depressed sufficiently so that it lies substantially in the plane of the portion, 2, of the base plate, thus permitting the button, 15, to be moved from the position, 15', to the position, 15, over the portion, 20, of the U-shaped element to secure it in place. The device is then in the position shown in Figs. 1 and 4.

When pressure is exerted on the door in the direction of the arrow shown in Fig. 4 the door is forced upwardly along the inclined surface, 3. Although the base plate was originally wedged quite tightly under the door there is enough resiliency in the rub-

ber block, 8, and in the door itself so that it rises slightly and moves towards the actuating means, 19, and contacts with it as shown in Fig. 4. The rubber block on account of its clinging action holds the plate in fixed position on the floor and the links, 17, in the U-shaped element, which is secured to the door, permit sufficient movement of the U-shaped element for this actuating contact to take place.

When the door is forced against the contact the links assume the position shown in Fig. 4, thus pressing the actuating element, 19, and releasing the bell ringing mechanism. The harder the door is pushed from the outside the more effective the wedging action becomes so that it is quite impossible to open the door with my stop in place, and so long as the door is being forced from the outside the alarm continues to ring.

While I have described my invention in its preferred embodiment it is to be understood that the drawings are merely illustrative, that the words which I have used are words of description rather than of limitation, and that changes, within the purview of the appended claims, may be made without departing from the true scope and spirit of my invention in its broader aspects.

What I claim is—

1. In a door stop, the combination with a base plate adapted to be wedged between the bottom of a door and its sill, of a wedged-shaped rubber block removably inserted in the bottom of said plate and adapted to frictionally engage the sill when said stop is in wedged position.

2. In a door stop, the combination with a base plate adapted to be wedged between the bottom of a door and its sill, of means attached to said plate for positively securing it to the door in wedged position.

3. In a door stop, the combination with a base plate adapted to be wedged between the bottom of a door and its sill, of means for positively securing the plate to the door; said means being slidably connected to the plate to afford a limited movement of the door relative to the plate.

4. In a door stop, the combination with a base plate of a rubber block forming with said plate a wedge adapted to be inserted between the bottom of a door and its sill, and means for positively securing the plate to the door; said means being slidably connected to the plate to afford a limited movement of the door relative to the plate.

5. In a device of the character described, the combination with a base plate adapted to be wedged between the bottom of a door and its sill, of an alarm and means adapted to be actuated by a slight opening movement of the door for placing said alarm in operation mounted on said plate, and means for securing the plate to the door; the securing

means being slidably connected to the plate to afford a limited movement of the door relative to the plate.

6. In a device of the character described, the combination with a base plate of a rubber block forming with said plate a slightly resilient wedge adapted to be inserted between the bottom of a door and its sill of an alarm and means adapted to be actuated by a slight opening movement of the door for placing said alarm in operation mounted on said plate, and means for securing the plate to the door; the securing means being slidably connected to the plate to afford a limited movement of the door relative to the plate.
